ADJUSTABLE SPRING SUPPORTED CHAIR

Renwick J. Sharp, Guatemala, Guatemala

Application November 14, 1944, Serial No. 563,334

12 Claims. (Cl. 155—51)

1

The present invention relates to improvements in chairs, particularly an adjustable chair for restaurants, malt shops, soda fountain counters and the like.

Among the objects of the invention are to provide improved revolving, swaying and adjusting mechanism for application to chairs to provide for their adjustability.

Further and more specific objects include the provision of a spring which can be flexed only in a lateral manner to cooperate with a ball support for the chair post wherein the post portion may sway; the provision of an improved spring construction for automatically regulating the position of the back of the chair in relation to the seat while the seat is being occupied; the provision of assembled parts permitting more adequate means for oiling and maintaining the associated parts lubricated; and to provide a chair which is more comfortable and appealing to incline prospective customers to visit the establishments where such luxury affords to the patrons a foretaste of the good things to follow.

With the foregoing and other objects in view, the invention further resides in the novel arrangement and combination of parts and in the details of construction hereinafter described and claimed, it being understood that changes in the precise embodiment of the invention herein disclosed may be made within the scope of that which is claimed without departing from the spirit of the invention.

Referring to the drawing wherein is shown what is now deemed to be a preferred embodiment of the invention,

Fig. 1 is a perspective view of the device,

Fig. 2 is a side elevation thereof,

Fig. 3 is an enlarged, fragmentary vertical midsection showing some parts in side elevation,

Fig. 4 is a transverse section taken on line 4—4 of Fig. 3,

Fig. 5 is a fragmentary section taken on line 5—5 of Fig. 2,

Fig. 6 is a detail view of the cantilever seat spring.

Referring in detail to the several figures and particularly first to Figs. 1 and 2, therein is shown a chair 1 having a seat bottom 8 supporting a padded apertured cushion 9. Bowed leaf springs 10 and 11 are provided with a pair of

2

flanges or ears 12 as shown in Fig. 5 located approximately midway between the ends of the springs, each ear having an aperture to receive a bolt 13 which spans the space between the flanges comprising the ears to engage apertured ear drums 14 formed in each rear corner portion of the seat bottom 8 thereby providing a support for the rear end of the latter. To the upper ends of the bowed springs 10 and 11 are fastened the padded back support 15, and the lower end of each spring is developed into a loop 16 loosely engaging the protruding end portions of a pin 17 carried by a sleeve 18 welded or otherwise fastened to the post 19.

On the underside of the seat bottom 8 at each front corner thereof is fastened by any suitable means a bracket 20 which embraces the body portion of a bowed, stirrup-shaped spring member 21 to support somewhat yieldingly in a cantilever fashion the front side of the seat bottom 8, the two arms 22 of the spring member 21 being deflected toward each other and securely fastened within the apertured cap plate 23 screwed onto the tubular post 19. Said spring arms 22 are both confined to the space at the front side of the post 19, and each of them has three curved parts.

The tubular post 19 is extensibly supported within a threaded socket 24 of a revolving and swaying member 25 by means of a threaded disk 26 screwed into said socket. The disk 26 has a rod 27 axially secured to it which is provided with an elongated loop 28 at its end, said loop interlocking with a similar loop 29 attached to a rod 30 which extends through the seat bottom 8 and has a handle 31 fastened to it for the purpose of adjusting the height of the seat bottom 8 and cushion 9 relative to the member 25. The rod 30 is mounted axially of the post 19 and the aperture 32 in the cap 23 permits of a wobbling movement of the rod 30 in said aperture. By referring to Fig. 3 it will be seen that the rod 30 extends through a hole 33 in the seat bottom and that a flanged collar 34 is secured to the rod in any suitable manner and held abuttingly against the underside of the seat bottom by means of the countersunk plate 35 riveted thereto. In Fig. 1 it will be seen that the handle 31 occupies the aperture in the cushion and is manually acces-

sible to any occupant of the chair desiring to use it to adjust the seat to suit their convenience.

A split collar 36, 36a, shown on an increased scale in Fig. 4, is utilized to seal the mouth of the socket 24, part 36 of the collar having a tongue 37 which travels in a groove 38 in the post 19 to prevent the latter from being withdrawn from the member 25 or rotated in relation thereto, each part 36, 36a being secured to the member 25 by means of a plurality of screws 39.

The revolving and swaying member 25 is cylindrically shaped and slightly below the bottom of the recess 24 it is outwardly flared at a point designated as 40 and then developed into a downwardly directed skirt 41 to overlie in a loose, surrounding manner the upper portion 42 of the flanged base 43. Said upper portion is shown contracted and has an annular recess 44 into which are projected the point portions 45 of a plurality of screws 46, said screws permitting revolving and swaying of the member 25 but preventing disengagement therewith.

The member 25 is mounted to revolve and sway upon the base 43 by means of a stiff spiral-cut spring 47 having a ball shaped globular end 48 seated in a socket 49 formed in said member 25 and having a screwthreaded portion 50 at the end opposite to said ball screwed into a threaded aperture 51 located axially of said base, a threaded bolt 52 being tapped into the hub 53 of the base and extending into the threaded portion of the cut spring to prevent rotation of the latter, there being a cavity 54 extending into said spring to a point adjacent said ball 48. At the juncture of the ball with the spiral cut portion 55 of the spring is an annular, arcuated recess 56 and a set screw 57 is screwed into said recess to maintain a fixed relation of the member 25 with the spring 47. The spiral cut in the spring 47 renders the same laterally resilient.

The recess 56 may be supplied with a lubricant through the tapped hole occupied by the screw 57 to maintain the globular head in its semi-spherical seat lubricated. Also, a lubricant may be introduced into the socket 24 before applying the split collar to maintain the threaded disk 26 and threaded portion of the socket 24 lubricated.

A foot rest, slidably mounted upon the post 19 and designated by the numeral 58, is provided for the feet of the occupant sitting in the chair, and fastening means 59 are provided for securing the base 43 to the floor 60.

Commenting further on the cut spring this member may be considered a new article of manufacture, since it is separately saleable. It comprises a circular body having a globular head at one end, is externally threaded at its opposite end, has a cavity opening out at the threaded end and extending from such end to a point adjacent said globular end, and has a spiral slit cut through the material between said threaded end and globular end, there being an annular, arcuated groove formed in the circular body subjacent to its globular end.

From the foregoing description the operation is believed to be understandable, except that in addition it may be well to state that the hinge axis of the seat bottom 8 is at the straight inner run 22a of the spring 21, said run being slightly turnable in relation to the seat so that when the springs 10 and 11 are depressed the seat back 15 will be urged against the "small" of the back of the person occupying the seat. This action is also dependent upon the fact that the pivotal connection 16 for the lower ends of the bowed

springs 11 is located in a considerably spaced relation to the ears 12.

The downward movement of the seat bottom 8 is limited to the point defined by the cap 23, and in the event springs 10 and 11 should ever collapse, the weight of the person sitting in the seat would be carried springlessly by said cap 23, the interlocking links 28 and 29 being of sufficient length to permit of this extreme depressing.

10 What is claimed is:

1. In a revolving and swaying adjustable height seat or chair, a seat bottom for supporting a cushion, a tubular post member, an apertured cap member screwed onto the upper portion of said post member, a two armed cantilever spring having the free end portions of its arms mounted in said cap member and its body portion extended horizontally and connected by bowed downwardly directed runs with said arms, said body portion underlying and being pivoted to the forward portion of said seat bottom, a pin having free end portions laterally mounted on said post member subjacent said cap member, a pair of bowed springs each having looped end portions at one end pivotally engaging the free end portions of said pin, means carried at their concave sides by the central arched portions of said bowed springs pivotally related to the rear portion of said seat bottom, and a seat back fastened to and spanning the distance between the other ends of said bowed springs.

2. The subject matter of claim 1, and brackets carried by the fore portion of said seat bottom and loosely encircling the horizontal portion of said cantilever spring at spaced apart points.

3. The subject matter of claim 1, and, a base, a vertically extending member rotatively mounted to sway on said base, said member having a vertically extending elongated socket in its upper end, and said post member being vertically adjustable in said socket.

4. The subject matter of claim 1 and, a base, a vertically extending member rotatively mounted to sway on said base, said member having a vertically extending elongated socket in its upper end, said post member being vertically adjustable in said socket, a split collar fastened to said rotatively and swaying member and enclosing the mouth of said socket in a surrounding relation to said post member, and an inwardly directed tongue carried by at least one of the members comprising said split collar to engage a vertically extending groove in the outer surface of said post member.

5. The subject matter of claim 1 and, a base, a vertically extending member rotatively mounted to sway on said base, said member having a vertically extending elongated socket in its upper end, said post member being vertically adjustable in said socket, a split collar fastened to said rotatively and swaying member and enclosing the mouth of said socket in a surrounding relation to said post member, an inwardly directed tongue carried by at least one of the members comprising said split collar to engage a vertically extending groove in the outer surface of said post member, said socket being threaded, a threaded disk screwed into said threaded socket supporting said tubular post and including a stem provided with a looped end occupying the tubular portion of said post member, said head being adjustable to support said post at various heights, a rod provided with a looped end interlocking with the loop of said stem, a portion of said rod also occupying a portion of the tubular part of said post

65

75

member and protruding through the aperture of said cap past the space between the latter cap and said seat bottom and thence extending through an aperture in said seat bottom into a hole in said cushion, a manually accessible handle mounted on the end of said protruding rod for rotating said head, a collar fastened to said rod in an abutting relation to the underside of said seat bottom, and means carried by said seat bottom to maintain said collar in said abutting relation.

6. In a chair of the kind described, a seat bottom for supporting a cushion, a tubular post member, an apertured cap member screwed onto the upper portion of said post member, a two armed cantilever spring having the free end portions of its arms mounted in said cap member and its body portion extended horizontally and connected by bowed downwardly directed runs with said arms, said body portion underlying and being pivoted to the forward portion of said seat bottom, a pair of bowed springs each having end portions at one end pivotally related to said post member subjacent to said cap member, means carried by the central arched portions of said bowed springs pivotally related to the rear portion of said seat bottom, a seat back fastened to and spanning the distance between the other ends of said bowed springs, a base, an elongated vertically extending member rotatively mounted to sway on said base, said member having a vertically extending elongated socket in its upper end, said post member being mounted in said socket in a vertically adjustable manner, said base having a reduced circular upper portion provided with a circumferential recess and said rotating and swaying member having its lower portion annular and vaulted and provided with a depending skirt adapted to loosely overlie and envelop said contracted circular upper portion of said base including said recess, there being an annular vaulted cavity in said annular vaulted lower portion and a cylindrical cavity superjacent said vaulted cavity terminating at its upper end in a semi-spherical seat, a vertically extending cylindrically shaped support provided with a globular head occupying said seat and having its lower end threaded and screwed axially into said base for supporting said rotating and swaying member in a vertically spaced relation to said base, said support having an elongated bore extending from its lower end to a point adjacent said globular head, there being a spiral groove cut in the wall of said support to render said wall resilient between said threaded end of said support and its globular head in order to provide for the swaying movement of said rotating and swaying member, and means carried by said skirt and occupying a portion of said recess to limit said swaying movement.

7. The subject matter of claim 6 and, there being an annular groove formed in said support subjacent said globular head, and a set screw screwed into said cylindrical cavity and occupying a portion of said annular groove.

8. In a chair of the kind described, a circular base having a contracted upper portion provided with an annular recess therearound, said base having an upwardly threaded central bore therein, an upstanding cylindrical hollow body provided at its top with a globular head and having its opposite end portion externally screwthreaded and screwed into said bore, there being a spiral slit cut through the wall of said body and extending from said threaded end to a point adjacent to said globular head to render the slit part flexi-

ble, an elongated vertically extending member provided with a hollow basal portion terminating in a downwardly directed skirt, said skirt circumferentially loosely surrounding said annularly recessed part of said base, the hollow within said elongated member being cylindrical throughout its upper portion and terminating in a semi-spherical seat wherein said head turnably fits, said skirt carrying means projecting internally therefrom into said recess to connect the parts together and to limit the swaying movement of said elongated member, and means to support a chair bottom upon said elongated member.

9. In a chair of the kind described, a base, an upstanding body provided at its top with a globular head and having its opposite end secured to said base, there being a spiral cut through the wall of said body between its anchored end and said globular head rendering the slit part flexible, an elongated vertically extending member provided with a hollow basal portion, the hollow within said elongated member being cylindrical throughout its upper portion and terminating in a semi-spherical seat wherein said head turnably fits, means carried by said hollow basal portion and cooperating with said base to limit the swaying movement of said elongated member, and a seat mounted upon said elongated member.

10. In a chair structure comprising an upstanding elongated body having a screwthreaded vertical bore extending downwardly into its upper end portion, an upstanding rod having a screwthreaded head fixed to its lower end, said head screwing adjustably into said bore, said rod being in upper and lower sections which are slidably connected to allow variations in the length of the rod, a tube resting on said head and slidably mounted in said bore, said tube loosely containing said rod, said tube projecting above the upper end of said bore and said rod projecting above the upper end of the tube, a chair seat, and means yieldingly supporting said chair seat upon and above the upper end of said tube, said rod being accessible above said chair seat for rotation to adjust the height of the screwthreaded head carried by its lower end, said rod having a bearing in said chair seat.

11. The subject matter of claim 10, and a handle means secured to the upper end of the rod for use in manually rotating the latter to adjust the height of the chair seat, a cushion resting upon said chair seat, said rod extending through said cushion and said handle means resting in a depression in the latter.

12. In a chair structure comprising an upstanding elongated body having a screwthreaded vertical bore extending downwardly into its upper end portion, an upstanding rod having a screwthreaded head fixed to its lower end, said head screwing adjustably into said bore, a tube resting on said head and slidably mounted in said bore, said tube loosely containing said rod, said tube projecting above the upper end of said bore and said rod projecting above the upper end of the tube, a chair seat, and means yieldingly supporting said chair seat upon and above the upper end of said tube, said rod being accessible above said tube for rotation to adjust the height of the screwthreaded head carried by its lower end thereby to regulate the height of said chair seat.
